YARD GOODS DISPLAY RACK

John B. Holck, 735 Judson St.,
Longmont, Colo. 80501

Filed Oct. 16, 1967, Ser. No. 9,005

Term of patent 14 years

(Cl. D80—10)

FIG. 1.

FIG. 2.

FIG. 3.

FIG. 4.

I claim:

The ornamental design for a yard goods display rack, as shown and described.
